L. M. CRARY,

RAILWAY TIE.

APPLICATION FILED MAR. 14, 1917. RENEWED MAY 3, 1918.

1,277,390.

Patented Sept. 3, 1918.

Inventor,

Louis M. Gary.

By

Alf Stater

Attorney

UNITED STATES PATENT OFFICE.

LOUIS MERTON CRARY, OF HONGKONG, CHINA.

RAILWAY-TIE.

1,277,390.

Specification of Letters Patent. Patented Sept. 3, 1918.

Application filed March 14, 1917, Serial No. 154,889. Renewed May 3, 1918. Serial No. 232,381.

To all whom it may concern:

Be it known that I, LOUIS M. CRARY, a citizen of the United States, residing at Hongkong, China, have invented certain new and useful Improvements in Railway-Ties, of which the following is a specification.

The present invention relates to railway ties, and the primary object is to provide a structure of this character that will resist the action of the elements, and at the same time constitute an effective sleeper or tie.

A further and important object is to provide a device of this character that will not slew or creep, is relatively flexible, so that it will not be liable to break if unevenly packed or tamped, and is furthermore constructed so that ordinary "dog" spikes, or other usual rail fasteners can be used without changing the methods or tools now employed in the construction and maintenance of railways.

An embodiment of the invention that is at present considered the preferable one is illustrated in the accompanying drawings, wherein:

Figure 1 is a top plan view of the tie,

Fig. 2 is a bottom plan view,

Fig. 3 is a side elevation,

Fig. 4 is a horizontal longitudinal sectional view on an enlarged scale through one of the sleeper members,

Fig. 5 is a vertical sectional view taken on the line 5—5 of Fig. 4.

Similar reference numerals designate corresponding parts in all the figures of the drawings.

In the embodiment illustrated, two separate sleeper members 6 are employed that are preferably constructed of concrete, granite or other stone chips 7 being embedded in the lower sides of the members before the concrete has set, said chips projecting below the lower faces of the members so as to roughen the same and produce anchoring surfaces that will assist in preventing the slipping or creeping of the tie.

The two members are connected by spaced tie elements 8 that are preferably in the form of metal rods square in cross section. The end portions of said rods are embedded longitudinally in the sleeper members and have vertical eyes 9 also embedded in the members and disposed out of transverse alinement. The upper sides of

the sleeper members 6 are provided with inclined rail seats 10, and located at the margins of said seats are the upper ends of vertical downwardly tapered rail fastener receiving plugs 11 that are embedded in the 60 sleeper members and pass through the eyes 9. These plugs are preferably of wood, so that rail fasteners of practically any well known type may be driven thereinto.

In the first place, it will be evident that 65 the structure is relatively simple and can be easily and cheaply manufactured. The concrete sleeper members being separate structures and connected by the tie rods, are thus permitted to have a relative play, 70 so that the danger of breakage of the tie due to uneven tamping, is eliminated. The end portions of the tie rod extending longitudinally through the sleeper members, serve as reinforcements therefor, and to 75 further reinforce the concrete structures, transverse rods of suitable formation, preferably twisted, may be employed, these rods being shown at 12. The tie rods furthermore serve as securing means for the plugs 11, 80 and these plugs being tapered, can be readily removed when they become decayed or incapacitated from any reason, so that new ones may be utilized without the necessity of an entirely new tie.

From the foregoing, it is thought that the 85 construction, operation and many advantages of the herein described invention will be apparent to those skilled in the art, without further description, and it will be understood that various changes in the size, shape, proportion and minor details of construction may be resorted to without departing from the spirit or sacrificing any of the 90 advantages of the invention.

Having thus fully described my invention, what I claim as new, and desire to 95 secure by Letters Patent, is:

1. In a railway tie, a sleeper member of concrete, anchor elements embedded in the 100 under side of said member and projecting below the under face thereof, and means for securing a rail to the sleeper member.
2. In a railway tie, a sleeper member of concrete, stone chips embedded in the under 105 side of said member and projecting below the under face thereof, producing a roughened anchor surface to prevent slipping of the tie, and means for securing a rail to the sleeper member.

3. In a railway tie, the combination with spaced sleeper members of concrete, of spaced substantially straight tie bars located side by side and connecting the members and having their end portions embedded longitudinally therein, said tie bars being each a single integral unitary structure and said bars having vertical openings through their embedded body portions, that are respectively at the inner and outer sides of the rails to be secured, and fastener receiving plugs embedded in the sleeper members and passing through the openings or eyes, said plugs being disposed in the longitudinal planes of the tie bars.
4. In a railway tie, the combination with spaced sleeper members of concrete, of substantially straight tie bars connecting the

members and having their end portions embedded longitudinally therein, said tie bars having vertical openings through their embedded body portions, fastener receiving plugs embedded in the sleeper members and passing through the openings or eyes, said plugs being disposed in the longitudinal planes of the tie bars, and anchor elements embedded in the under sides of the sleeper members and projecting below the under faces thereof, the tie bars being arranged above said anchor elements.

In testimony whereof, I affix my signature in the presence of two witnesses:

LOUIS MERTON CRARY.

Witnesses:

GEORGE E. ANDERSON,

JAMES CLINE,
